UNITED STATES PATENT OFFICE

CONRAD BERGMANN, OF PHILADELPHIA, PENNSYLVANIA, ASSIGNOR TO COLUMBIA STEEL EQUIPMENT COMPANY, OF PHILADELPHIA, PENNSYLVANIA, A CORPORATION OF PENNSYLVANIA

FOLLOWER BLOCK

Application filed January 7, 1929. Serial No. 330,728.

This invention relates to a follower block for a filing cabinet or the like, and is more particularly concerned with a new and improved manner of supporting and adjusting the follower block.

An object of the invention is to produce a new and improved form of follower block.

Another object is to produce a follower block on which pivotal arms are arranged to normally engage stops along the side of a filing cabinet.

Another object is to produce a follower block on which arms are pivotally mounted, the arms engaging stops along the side of a filing cabinet, which stops normally permit movement in one direction only.

Another object is to produce a follower block readily removable from a filing cabinet.

Still another object is to produce a follower block having a readily demountable locking means.

Yet another object is to produce a follower block for a filing cabinet having locking means therefor, the said means being readily demountable as a result of the removal of a pin.

Other objects will appear hereinafter.

In the drawings which illustrate one example of my invention,

Fig. 1 is a vertical transverse section through a drawer or compartment of a filing cabinet employing a follower block in accordance with my invention;

Fig. 2 is a fragmentary section taken on the line 2-2 of Fig. 1;

Fig. 3 is a section taken on the line 3-3 of Fig. 2, and showing details;

Fig. 4 is a sectional view illustrating the contact shoe when removed from engagement with the upstruck ratchet elements;

Fig. 5 is a perspective view illustrating the locking arms associated with the bearing members, while

Fig. 6 illustrates the details of the locking means.

At 1 is shown the front of a drawer or compartment of a filing cabinet having a drawer portion comprised principally of the member 2 of substantially channel section having

a longitudinally-extending recess 3 in the bottom thereof, also of substantially channel section, and having outwardly-turned horizontally extending flanges 4 and 5 at the longitudinal extremities thereof. In order to properly reinforce the drawer, the member 2 is preferably provided at its corners with angle members 6 and 7 which act as bearings for the compartment against the guide plates of a filing cabinet.

To further reinforce the drawer or compartment, the lower extremities of the bearing members 6 and 7 are downturned to provide flanges 8 and 9. The flanges 4 and 5 preferably engage and are suitably secured to suitable angle members 10 and 11, said angle members providing outwardly extending recesses. As will be evident from an inspection of Fig. 2, each recess is provided with a plurality of instruck portions 12, all extending in the same direction, for a purpose which will be described hereinafter.

Bearing members 13 having a central web 14 and side flanges 15 and 16, rest on the flanges 4 and 5 and are movable therealong. At one end thereof, each bearing member 13 is provided with a member 17 extending upwardly for a short distance from the lower flange 16. Above the members 17, arms 18, extending at right-angles to the web 14 and secured thereto by means of portions 19 bent at right-angles to the main portion 18, are adapted to impart movement to the bearing members 13 along the flanges 4 and 5, respectively. It will be noted that in the normal position of the bearing member 13, the stop member 17 is adapted to ride by the upstruck ratchet elements 12 when it is impelled in one direction but to contact with the sharp edges thereof when an attempt is made to draw it in the opposite direction.

Each arm 18 is preferably passed through a slot in an angularly bent portion of a guide member 20 said members being provided along the vertical edges of a follower plate 21. These guide members 20 are the sole supports on the follower plate for the arms 18 and the locking means therefor, which are to be described hereinafter. The arms 18 are provided with notches 22, as shown in Figs. 100

1 and 5, which pass through co-operating openings 23 and 24 arranged in a lifting plate 25. It is to be understood that the openings 23 and 24 are to be of greater extent than the 5 width of arm material remaining after the notches 22 have been cut therein, in order to permit pivoting of the arms about the openings. Retaining members 26 abut the rear of plate 25 and are shown as being provided on their adjacent ends with outturned flanges 27 and 28 passed through a slot 29 in the lifting plate 25 and being secured therein by suitable retaining means such as a cotter pin 30. Preferably, the bearing members are formed of dissimilar material from that of the recesses. For instance, if the recess is painted in keeping with the remainder of the drawer, the bearing members will be of bare metal, to prevent adhesion between the 20 surfaces.

When the arms 18 have been passed through the guide members 20 and through the orifices 23 and 24 in the lifting plate 25 and are secured in position by the cotter pin 30, they 25 are then in a position to be lifted upwardly as a result of vertical movement of the lifting plate 25. As will be obvious from an inspection of Fig. 4, such lifting movement of the arms 18 results in an inward movement of 30 the contact shoe 17 and a corresponding outward movement of the flange 15 of the bearing member 13. This withdraws the contact member 17 from the line of contact with the ratchet member 12 and permits sliding of the follower block 21 in either direction. A spring 31 is secured at 32 to the lifting plate 25 and at 33 to the follower block 21, which acts to return the contact shoe 17 into registration with the ratchet members 12, upon release of the lift member. With the ratchet members upstruck in the direction shown in the drawings, the follower plate can be moved rearwardly of the filing compartment without actuation of the locking mechanism.

45. In the event that it is desired to bring the follower plate forward however, it is necessary only to actuate the lifting plate 25 by means of applying upward movement to the finger member 34.

50. It will thus be seen that a neat and novel construction is produced as a result of my invention, susceptible to numerous modifications, and it is intended that the scope of the invention be limited only by the accompanying claims.

I claim:

1. In a filing compartment having side walls, longitudinal recesses extending therealong, ratchet members arranged longitudinally of the sides of said side walls, a follower block within said cabinet arranged transversely of said side walls, bearing means for said follower block extending along said recesses and having a contact member 60 thereon for contacting with said ratchet mem-

bers to normally permit movement of the follower block in but a single direction, and a single means for actuating both bearing members to release the contact member to permit movement of the follower block in both directions. 70

2. In a filing compartment having recesses along the sides thereof and ratchet members along the sides of said recesses, a follower block, and elongated guide members for said follower block, movable along said recesses, each guide member having an outturned, vertically extending flange forming a stop member at one end thereof, normally cooperable with said ratchet members to lock the guide members in one, but not in the opposite direction. 75

3. In a filing compartment having recesses extending along the longitudinal sides thereof, said recesses each having a longitudinally extending ratchet member therein having substantially vertically-arranged teeth, a follower block, arms pivotally mounted on said follower-block and extending outwardly from the sides thereof, guide members in said recesses, to which said arms are connected, and a stop member on each of said arms, cooperable with said ratchet member to normally lock the follower block in a single direction 90 only. 95

4. A filing compartment having recesses extending along the interior of the longitudinal walls thereof, a ratchet member extending longitudinally of each of said recesses, said ratchet member having substantially vertically-arranged teeth, a follower block, arms pivotally mounted on said follower block and terminating in bearing members traversing said recesses and being provided with stop members normally engaging said ratchet members to lock the follower block in one direction only, and a single instrumentality on said follower block, by which said arms may be actuated about their pivotal mountings to disengage the contact shoes from the ratchet members, whereby the follower block may be moved in both directions. 100 105 110

5. In a follower block for a filing compartment wherein the follower block is normally prevented from movement in one direction by means of pivotally mounted arms normally engaging ratchet members vertically-arranged along the interior of the longitudinal walls of said compartment, a single instrumentality for disengaging said arms from said ratchet members comprising a plurality of retaining members provided at their adjacent edges with flanges extending in the same direction, a lifting plate having a finger engaging member, a longitudinal slot therein through which said flanges extend, a locking means securing said flanged ends in place in said slot, said arms engaging said locking plates, whereby motion of the lifting plate is imparted to the arms. 115 120 125 130

6. In a filing compartment, side walls, in-turned ratchet members instruck along said side walls and arranged in longitudinal series therealong, a follower plate in said compartment, arms pivotally engaging said follower plate along the sides thereof in such manner that they are adapted to swing through substantial vertical angles, said arms extending outwardly from said follower plate to normally abut said inturned ratchet members and having engagement therewith permitting movement of the follower plate in one direction but contacting with said ratchet members to prevent movement in the opposite direction and a single means on said follower plate for actuating said arms to remove them from contact with the ratchet members to thereby permit free movement in both directions.
7. In a follower block for a filing compartment having locking means along the sides thereof, arms pivotally mounted on said follower block and terminating in bearing members, guide members on said follower block through which said arms extend, a lifting plate having inturned flanges along its longitudinal edges, said lifting plate having recesses adapted to receive and guide the said arms and a longitudinal opening therein, retaining members having their adjacent ends flanged and extending through said opening, said retaining members abutting said lifting plate adjacent said recesses to secure the arms in place, and said inturned flanges of the retaining members being secured together, whereby vertical movement of the lifting plate will result in consequent pivoting of the arms.
8. In combination with a filing compartment having opposed side walls adjacent faces of which are provided with longitudinally-extending ratchet members, a transversely-extending plate arranged between said side walls, transversely-extending arms pivoted adjacent side edges of said plate and adapted to coact with said ratchets at their outer ends and means supported and guided from the follower plate and having engagement with the inner ends of said arms for simultaneously vertically shifting said inner ends to cause disengagement of the outer ends from said ratchets.
9. In combination, a follower plate having pivots adjacent its side edges, arms engaged with said pivots, a vertically slidable member at the center of the plate having engagement with the inner ends of said arms and means normally maintaining said slidable member in a position projecting the outer ends of said arms to the greatest possible extent.
10. In a filing compartment having recesses along the sides thereof providing bearings, a follower block, bearing members fitting in said recesses, a plurality of transverse-
- ly arranged arms pivoted on said follower block and each having a flanged portion secured to one of said bearing members and having a notch adjacent its inner end, and a single lifting plate arranged between said arms in which the notched portions of the arms engage, said lifting plate having rearwardly-extending flanges adjacent its sides, said flanges having vertically-elongated recesses therein, which recesses are adapted to pivotally receive the notched portions of the adjacent arms whereby lifting movement imparted to the plate will be translated to pivot the arms on the follower block about the fulcrums provided by the lowermost edges of the recesses, and means for holding and guiding said lifting plate.
- CONRAD BERGMANN.
